UNITED STATES PATENT OFFICE.

ARTHUR ORLOFF, OF GREEN BAY, WISCONSIN, ASSIGNOR TO NORTHWEST ENGINEERING COMPANY, OF GREEN BAY, WISCONSIN, A CORPORATION OF WISCONSIN.

POWER SHOVEL.

Application filed February 29, 1924. Serial No. 695,941.

To all whom it may concern:

Be it known that I, ARTHUR ORLOFF, a citizen of the United States of America, and resident of Green Bay, in the county of Brown and State of Wisconsin, have invented new and useful Improvements in Power Shovels, of which the following is a description, reference being had to the accompanying drawings, which are a part of this specification.

The invention relates to power shovels.

In power shovels in which the dipper and its handle or stick are mounted to swing and shift relative to its supporting boom, it is sometimes necessary and highly desirable to hoist the dipper when the stick is in an extended position so that the contents of the dipper may be deposited at the desired point. In machines of this general type a dipper stick of reasonable length can be thrust out when about in horizontal position, but hoisting from then on will gradually retract the dipper and stick until finally the sheave associated with the dipper meets the sheave at the outer end of the boom so that some means are necessary to hold the stick in extended position. It has heretofore been quite common practice in some designs of shovels of this general type to use a brake controlled by the operator, either by hand or by foot, to prevent the retraction of the extended stick, but such constructions put an additional duty on the operator and complicate the control mechanism. The object of this invention is to provide automatically operating means whereby the stick once thrust out at or near its limit is prevented from moving inwardly during hoisting, such means operating without complicating the control, as by additional levers, and without adding to the duties of the operator.

A further object of the invention is to provide means whereby dipper sticks substantially longer than the distance between the shipper shaft and the point of the boom may be successfully hoisted in the extended position without complicating the controls.

A further object of the invention is to associate an automatic brake with the dipper operating mechanism so that the brake is automatically released or stays released during the outward movement of the stick; is automatically applied when forces, other

than the retracting means proper, are acting to shift the stick inward; and, is automatically released when the stick is retracted.

A further and more particular object of the invention is to provide a shovel of the rope-thrusting type in which the tension of the inward thrusting line is utilized to effect the release of an automatic brake so arranged as to restrain inward translation of the stick except when such tension is applied.

The invention further consists in the several features hereinafter set forth and more particularly defined by claims at the conclusion hereof.

In the drawings: Fig. 1 is an elevation view of an excavating machine embodying the invention; Fig. 2 is a plan view thereof, parts being shown in section; Fig. 3 is a detail sectional view taken on the line 3—3 of Fig. 2; Fig. 4 is a detail sectional view taken on the line 4—4 of Fig. 2.

In the drawings the numeral 5 designates the boom, which may be of any suitable construction, vertically pivotally attached at its lower end to the rotating base 6 of the machine, which base is of well known construction. A hoisting drum 7 and an auxiliary drum 8 are mounted on the base 6 in any suitable manner and driven from the prime mover, not shown, on the base. The drums 7 and 8 may be of any well known construction equipped with clutches and brakes to control their operation. The boom is adapted to be raised and held in various positions of vertical adjustment by any well known means, such as cables 9 connecting pulleys 10 at the outer end of the boom to parts on the rotating base. The boom shown is of the plate girder type with the dipper handle 11 working between its sides.

A shipper shaft 12 is secured in a support 13 on the boom and the saddle blocks 14 are loose on the shaft. The dipper handle shown is made in two sections and has a metal covering 11'. Each section of the handle is mounted to slide between the adjacent saddle block and a flanged roller 15 loose on said shaft 12. Sheaves 16 and 17 are journaled on the shaft 12 between the rollers 15. The dipper or shovel 18 may be of any suitable construction and is mounted, as usual, at the lower end of the dipper handle.

A hoisting cable 19 dead-ended on the drum 7 passes therefrom over a sheave 20 loose on a shaft 21 at the outer end of the boom, then around a transversely disposed 5 padlock sheave 22 pivotally mounted on the dipper and around the larger part of a compound drum 23 on which it is dead-ended. A cable 24 is dead-ended on the small side 25 of the compound drum 23 and passes one 10 or more times around the drum or sheave 16 on the shaft 12 and is dead-ended at 26 near the upper end of the dipper stick or handle 11. A cable 27 secured to and wound upon the drum 8 passes over the sheave 17 15 on the shaft 12 and is dead-ended at 28 at the lower end of the dipper handle.

With the construction above described, when the drum 8 is prevented from turning by its brake, thereby holding the line or cable 27, and the line 19 is pulled in, the dipper moves approximately in the arc of a circle of which the shipper shaft is the center. If it is desired to crowd into the material being excavated, or to move the dipper farther out, as in loading a wagon, the braking 20 effect on the line 27 is released slightly, allowing the line 19, pulling on the larger side of drum 23, to put a pull, here greater than hoisting effect because of the compound 25 drum, on line 24, which thereupon forces the dipper stick outward. Conversely, if it is desired to move the dipper farther in, hoisting with line 27 produces this effect. While the compound or differential drum is preferred, it is to be understood that the invention 30 is not to be limited thereto. Thus, by a proper manipulation of the lines 19 and 27 any desired swinging and thrusting movement of the dipper and its handle may be effected. Furthermore, since the line 24 35 which effects the thrust is actuated by the hoist, a crowding effect equal to the full driving force of the engine is secured.

With this and other constructions, however, when the stick is in an extended position and hoisting is continued until the stick is approaching, at, or above the horizontal, the hoisting cable 19 and other forces, such as the weight of the dipper and its contents, 40 tend to shift the stick inwardly.

To restrain the inward shifting movement of the dipper handle, a part of the drum 23 is formed as a brake-drum 29 adapted to be engaged by a brake-band 30. One end 31 of this band is adjustably secured to one arm of a bell crank lever 32, loose on a shaft 33 fixed on the boom, and at a greater distance from the center of said shaft than the point at which the other end of the band is secured to the other arm of said bell crank lever, thereby 45 providing an automatic brake which, when the drum 23 rotates in a clockwise direction, as in outward shifting of the dipper handle, acts to automatically release said band, and in a counterclockwise direc-

tion it acts to tighten said band about the drum 29. An arm 34 is also formed as a part of the lever 32 and a spring 35, secured at one end to said arm and at its other end to the boom, acts to put an initial tension in said band. As the inward shifting tendency of the stick when in an extended position acts through cable 24 to rotate the drum 23 in a counterclockwise direction, it will be noted that under these conditions the restraining torque of the brake is applied directly to the differential or compound drum 23 and is transmitted through the cable 24 to the dipper handle to hold the same.

In order to release the automatic brake 50 when it is desired to shift the dipper handle inwardly, the retracting cable 27 has a brake-operating means associated with its run between the drum 8 and the sheave 17. This means consists of a bell crank lever 36 55 pivotally mounted intermediate its ends on shaft 36' on the support 13 and operatively connected at its lower end by a link 37 with the arm 34. The upper end of said lever 36 carries a roller 38 engaged by said run of 60 said cable 27 to form what may be termed a bight therein, whose magnitude diminishes when tension is produced in said run by the inward pull of the cable 27, and which action causes the upper end of said lever 36 65 to be swung upwardly and, consequently, through said lever, link 37 and arm 34 shift said bell crank lever 32 so that its longer arm swings toward the shaft 21 and thereby releases the brake so that the brake is automatically released incident to the operator 70 shifting the dipper handle inwardly, and hence no additional control mechanism has to be operated by the operator.

It will be noted that I have provided 75 means which automatically restrain the dipper stick from moving inwardly, which means is released through cooperation with a run of the retracting cable.

I desire it to be understood that this invention is not to be limited to any specific form or arrangement of parts except in so far as such limitations are specified in the claims.

What I claim as my invention is.

1. In an excavating shovel, the combination of a boom, a dipper and dipper handle mounted on said boom for swinging and shifting movements relative thereto, means for hoisting the dipper, means including a cable for shifting the dipper handle in one direction, means for restraining the shifting of the dipper handle in that direction, and means to release said restraining means including a member engaging a run of said cable and moved by the operating tension in the cable.

2. In an excavating shovel, the combination of a boom, a dipper and dipper handle mounted on said boom for swinging and

- shifting movements relative thereto, means for hoisting the dipper, means including a cable for shifting the dipper in one direction, means for restraining the shifting of the dipper in that direction, means biased toward shifting movement in one direction and engaging a run of said cable to be shifted thereby in that direction to release said restraining means.
- 10 3. In an excavating shovel, the combination of a boom, a dipper and dipper handle mounted on said boom for swinging and shifting movements relative thereto, means for hoisting the dipper, means including a cable for shifting the dipper handle in one direction, means for restraining the shifting of the dipper in that direction, and means to release said restraining means including a lever having a part engaging a run of the
- cable and shifted by the operating tension 20 in the cable.
4. In an excavating shovel, the combination of a boom, a dipper and dipper handle mounted on said boom for swinging and shifting movements relative thereto, means for hoisting the dipper, means including a 25 hoisting drum, a sheave and a cable from said drum running over said sheave and having connection with said handle for shifting the dipper inwardly, means for restraining the inward shifting movement of the dipper handle, and means to release said restraining means including a member engaging the run of said cable between said 30 sheave and drum and moved by the operating tension in said cable.
- 35

In testimony whereof I affix my signature.

ARTHUR ORLOFF.
